UNITED STATES PATENT OFFICE.

JOSEPH J. HILLER AND ERNEST R. STRENGER, OF PHILADELPHIA, PENNSYLVANIA,
ASSIGNORS OF ONE-THIRD TO LOUIS J. VENUTO, OF PHILADELPHIA, PENNSYLVANIA.

WINDOW-CLEANING DEVICE.

Application filed August 3, 1920. Serial No. 400,955.

To all whom it may concern:

Be it known that we, JOSEPH J. HILLER and ERNEST R. STRENGER, citizens of the United States, residing, respectively, at 5 Philadelphia, in the county of Philadelphia and State of Pennsylvania, have invented certain new and useful Improvements in Window-Cleaning Devices, of which the following is a specification.

10 The object of this invention is to provide an improved construction of a mechanism for cleaning both the inside and outside of a window-sash simultaneously and to the same extent.

15 Many devices for this purpose have been devised, but apparently without overcoming certain defects which appear to be adherent in substantially all of them, and it is with this in view that many details have been 20 added, as hereinafter described, all of which are fully disclosed in the following description when read in conjunction with the accompanying drawings, in which Fig. 1 is a front elevation of the preferred embodiment of the device attached to a fragmentary portion of a window-sash and surrounding frame; Fig. 2 is a vertical section through the sash and frame showing the improved cleaner in side elevation; and Fig. 25 3 is a section on the line 3—3 of Fig. 2.

30 Referring to the drawings, the device will be considered as being applied to any usual type of transparent window-glass 1, surrounded by a frame 2, positioned against the usual molding portion 3, and held in place by any suitable form of removable molding 4. The frame 2 is additionally provided with a transversely extending aperture 5, through which extends in rotatable 35 engagement a rod 6, which at one end may if desired be provided with a handle-wheel 7 adjustably secured to said rod in any suitable manner as by means of a set-screw 8.

40 Secured to the opposite face of the said frame 2 are discs 9 provided with apertures 10 in alignment with the aperture 5 in the window-frame, and through which extends the rod 6. These discs 9 are secured to the frame in any suitable manner as for instance 45 by means of screws or transversely extending bolts 11, while said discs are provided with downwardly extending portions 12 provided upon their adjacent surfaces with enlarged bosses 13 extending centrally, which latter 50 are apertures for receiving screws 14.

Surrounding the rod 6 and adjustably secured thereto as by means of set-screws 15 are pinions 16, which are adapted to mesh with the gear-like portion 17 of a member revolvably secured to the outer face of the 60 depending portion 12 of each of the plates 9 by means of the screws 14.

Extending thence downwardly from the gear portion 17 are integral angle bars 18, to which are removably secured in parallel 65 relation rods 19, so that pieces of rubber, felt, or other material 20 can be removably yet firmly positioned between said last-named members 18 and 19, and when positioned as shown in Figs. 2 and 3 the elements 70 20 will bear against the opposite surfaces of the transparent glass 1, and equally throughout their longitudinal extent.

By grasping the knob 21, the bar 18 to which it is directly secured can be oscillated throughout substantially 180 degrees around the screw 14 as a pivot, and by virtue of the gears 16 and 17 the rod 18 upon the opposite surface of the sash member 1 will be oscillated to the exact same extent and simultaneously therewith.

75 In using the hand-wheel 7, it is obviously only necessary to make substantially a half-turn in either direction, or alternately in opposite directions with said wheel, and the rods 8, together with the cleaning members 20, will be oscillated as hereinbefore described with less angular motion of the arm of the operator.

80 Although one form of the invention has been described, it is to be understood that various alterations might be made in the details of construction without departing from the scope of the appended claim.

85 Having thus described our invention, what we claim and desire to protect by Letters Patent of the United States is:—

90 A window-cleaning device, comprising a pair of plates having aligned apertures, said plates adapted to be positioned upon the opposite sides of a window frame, means to removably attach each of said plates to said frame independently of the other of said plates, each of said plates having a depending portion, a rod extending through said frame and through the aperture in each plate and forming the only connection between said plates, a pair of gears carried by said rod upon the opposite sides of said plates, means also carried by said rod to 100 105 110

permit direct manual rotation thereof, a gear pivotally carried by the depending portion of each of said plates and meshing with said first gears, and cleaning members forming extensions of each of said gears and adapted to be oscillated across the opposite surfaces of a pane supported by said frame

by means of the oscillation of said rotating means.

In testimony whereof we have affixed our ¹⁰ signatures.

JOSEPH J. HILLER.
ERNEST R. STRENGER.
